VALVE OPERATOR

Willem E. Tupker, Sepulveda, Chester Richard LeWan, La Crescenta, and Antoni Tadeusz Bronikowski, Los Angeles, Calif., assignors to Bell Aerospace Corporation, a corporation of Delaware

Filed Feb. 14, 1969, Ser. No. 15,783

Term of patent 14 years

Int. Cl. D23—99

U.S. Cl. D23—167

FIG. 1 is a front elevational view of a valve operator showing our new design;

FIG. 2 is a rear elevational view thereof;

FIG. 3 is a top plan view thereof; and

FIG. 4 is a side elevational view thereof.

We claim:

The ornamental design for a valve operator, as shown.
